UNITED STATES PATENT OFFICE.

RALPH M. NORTH, OF VERONA, NEW JERSEY.

BROODER.

No. 834,401.

Specification of Letters Patent.

Patented Oct. 30, 1906.

Application filed February 12, 1906. Serial No. 300,760.

To all whom it may concern:

Be it known that I, RALPH M. NORTH, a citizen of the United States, residing at Verona, in the county of Essex and State of New Jersey, have invented new and useful Improvements in Brooders, of which the following is a full, clear, and exact specification, reference being had to the drawings forming a part hereof.

This invention relates to brooders in which artificial heat is employed to maintain a uniform temperature for the comfort of the occupants, usually chicks, and serve as a substitute for the brooding by the mother-hen; and the objects of my invention are to provide a heat distribution similar to that obtained from the mother-hen in natural brooding and means for insuring its even control, together with a readily-accessible and readily-cleaned brooder-house and a simplified device for the prevention of crowding among the chicks.

Other advantages will be apparent from the specification.

In the drawings, Figure 1 is a side view, partly in section, showing the interior of the brooder-house embodying my invention. Fig. 2 is a vertical cross-sectional view on the line 2 of Fig. 1. Fig. 3 is a horizontal cross-sectional view of the hover-space on the line 3 of Fig. 1 and showing in plan the removable floor-slats of the brooding-chamber. Fig. 4 is a view from below looking up into the heat-distributing chamber, and showing the manner of attachment of this part to the floor of the brooding-chamber. Fig. 5 is a cross-sectional detail, on an enlarged scale, of the adjustable heat-deflector. Figs. 6 and 7 are enlarged cross-sectional details of the means for attaching the heat-distributing chamber to the floor of the brooding-chamber. Fig. 8 is a perspective of the central slat of the removable floor-slats. Fig. 9 is a horizontal cross-sectional detail of the slide in which the window-frame 56 is mounted.

Similar numerals designate corresponding parts throughout the several views.

The brooder-house 1 is in the shape of an elongated box, having the sides 2 and ends 3 4 and is without a bottom except for the narrow strip 5, on which stands the lamp or other source of heat 6. The covers of the brooder-house consist of the removable pieces 7 8, arranged to be supported upon the upper edges of the sides 2, with moderate inclinations, as shown, to facilitate the escape of

rain. The cover 7 is provided on its under surface with two transverse cleats 9, which are received in notches 10 in the upper edges of the sides 2, thus retaining the cover 7 in position. The cover 8 has a transverse groove 11 near its upper edge to receive the upper edge of the cover 7. A cleat 12, arranged transversely on the under surface of the cover 8, engages in notches 13 in the upper edges of the sides 2 to hold the cover 8 in place, and hooks 14, engaging with staples in the sides 2, serve to lock the cover 8 securely in position. The cover 8 being secured in position, it follows that the cover 7 is also held in position by reason of the engagement of its upper edge in the groove 11 of the cover 8. By this arrangement ready access is afforded to the interior of the brooder-house, the release of the hooks 14 permitting the removal of the entire upper cover of the house.

The interior of the brooder-house is divided, broadly speaking, by a substantially horizontal floor into an upper and a lower compartment, the upper compartment above the floor containing the brooding-chamber 15 and play-chamber 16, separated from each other by the curtain 17, suspended from a strip 18, extending between the sides 2. Windows 19 in the sides 2 give light to the play-chamber. From the floor 20 of the play-chamber 21 on a slight incline leads up to the floor 22 of the brooding-chamber. The end 3 of the brooder-house next the play-chamber is provided with a slide 23, which may be raised and lowered to serve as a door when it is desired to permit the chicks to reach the open air. The slide may be secured in raised position by means of a pivoted button 24, capable of engagement with a notch 25 in the end 3.

The lower compartment of the brooder-house is divided by a partition 26 into the lamp-chamber 27 under the brooding-chamber and an air-chamber 28 under the play-chamber and runway, the air being trapped in the forward portion of this chamber under the play-chamber floor, so as to form a sort of dead-air space under the play-chamber. Port holes or openings 29 admit air to the air-chamber at a point near the partition 26, and as the partition does not extend entirely to the ground a current of fresh air may thus pass continually from the port-holes and air-chamber to the lamp-chamber around the lower edge of the partition 26. This arrangement while affording a plentiful supply of air

for combustion avoids a direct draft on the lamp and the consequent danger of extinguishing it, as would be likely to occur if the port-holes were located in the walls of the lamp-chamber. A door 30 in the end 4 at the front of the lamp-chamber gives access to the lamp and is provided with a window 31. Another window 32 in the end 4 at the front of the brooding-chamber facilitates inspection of the interior and serves to attract the chicks from the runway into the warmer brooding-chamber, since chicks naturally run toward the light. The window 32 is mounted in a frame 56, working in a vertical slide 49, so that it can be removed when the cover 8 is off, thus providing an opening through which dirt may be scraped out from the brooding-chamber floor.

It is the natural tendency of chicks to crowd together for warmth, with the result that the smaller and weaker ones are trampled on or smothered. This is a serious drawback to the practicability of many brooders, since in them this tendency is assisted rather than hindered by the provision within the hover of free open spaces within which the chicks crowd together, each struggling to get near the warmest portion of the hover by jumping upon or burrowing under one another. This objectionable tendency may be overcome by the interposition of obstacles to the free massing or crowding of the chicks, located at the points where it is found that the chicks congregate most compactly—namely, at the warmest points. To this end I provide posts 38, interspersed throughout and traversing the hover-space and spaced apart, so that while they permit the free passage of individual chicks between them they interpose a positive obstruction to any attempt of the chicks to mass together, jump upon, or burrow under one another, and break up into a number of small groups the otherwise compact brood. These posts extend from the bottom to the top of the hover-space, and I make them of hollow tubing to provide flues or air-passages within them for a purpose to be presently described.

In the construction of my special heating means I have endeavored to copy as closely as possible the distribution of heat as found in natural brooding, wherein the chicks receive the heat from above and from the sides or from the body, wings, and legs of the mother-hen. A rectangular opening in the floor of the brooding-chamber receives a metallic plate 33, which rests on buttons 34 at the sides of the opening, these buttons being employed for a special purpose which will be explained later. Depending from this plate and removably attached thereto by two fixed cleats 35 and two pivoted buttons 36 (see Figs. 4, 6, and 7) is an inverted hollow metallic cone 37, with its apex cut off to form an opening into which the top of the lamp-chim-

ney projects. This inverted cone receives a current of hot air from the lamp and acts as a heat-distributing chamber below the floor, serving to direct the hot-air currents upwardly into the flues of the posts 38, arranged to connect at their lower ends with a series of openings in the metallic plate 33. The heat-distributing chamber 37 serves also by radiation to warm the air in the upper part of the lamp-chamber, and thus very slightly to warm such portions of the floor of the brooding-chamber as are not included within the circumference of the upper end of the heat-distributing chamber 37. It is not good for the chicks to have too much heat on the legs; but I find it very desirable to take the chill off the floor, and this is perfectly accomplished by the radiation from the chamber 37, as above mentioned. The posts 38 are united to the metallic plate 33 at their lower ends in any suitable way. After traversing the hover-space the flues in the posts 38 discharge at their upper ends through openings in a plate 39 into a cone-shaped chamber or heat-radiator 40 within the brooding-chamber 15, the plate 39 serving as the base of the cone and being fastened to the upper ends of the posts 38 in the same manner as is the plate 33 at their lower ends. The heating-flues in the posts 38 by passing through the floor and traversing and discharging beyond the hover-space thus connect the source of heat and the heat-radiator. Leading from the upper end of the heat-radiator is the smoke-pipe 41, provided with a damper 42 and discharging through a suitable opening 43, preferably located in one of the sides 2 of the brooding-house, as shown, to prevent the entrance of rain. The smoke-pipe fits loosely in the opening 43 with free play, so as to admit of adjustment, as will be described later.

The space above the brooding-chamber floor included between the metallic plate 33 and the plate 39 of the heat-radiator is the hover-space and is warmed both by the heat radiated from the posts 38 and the heat-radiator 40. The floor beneath the hover-space is specially constructed so as to admit of removal for cleaning and is composed of a series of removable slats 44, arranged to rest upon the fixed or permanent portion 22 of the floor, these slats having notches along their sides at the proper intervals to receive the posts 38. By turning the slats up edge-wise they may be withdrawn from between the posts and cleaned, afterward being restored to position. The central slat 45, in addition to the notches along its sides, is provided with a short tongue, designed when in position to fill the space adjacent one of the posts 38. (See Figs. 3 and 8.) By taking off the cover 8 the heating apparatus may be lifted out in its entirety, carrying the removable slats 44 45 with it.

The arrangement of the posts 38 with inter-

rior hot-air flues is of additional advantage in preventing the crowding of the chicks, since this construction affords a plurality of heat centers, all at a uniform temperature, about 5 which the chicks may cuddle, instead of one heat center only, as usual heretofore. Many brooders by having but one heat center naturally draw the chicks to it, as it necessarily becomes the warmest place in the brooding-10 chamber, and thus crowding is induced. By supplying numerous centers of equal temperature I am enabled to make every portion of the brooding-chamber show the same degree of heat. The warm posts 38 are also a 15 serviceable substitute for the legs and wings of the mother-hen, since from them the chick receives on its sides the heat that it would ordinarily receive in like manner from the legs and wings of its mother, while at the same 20 time the heat supplied by the flues to the heat-radiator 40 above the hover-space is radiated downward upon the chick, like the heat from the body of the hen.

It is desirable to have the hover-space only 25 slightly greater in height than the height of the chicks otherwise the chicks jump upon or burrow under one another. As the chicks grow in height the hover-space must be adjusted in height from time to time to accommodate 30 their increase in height. For this purpose I have arranged the buttons 34, already mentioned as used for a special purpose, to support the metallic plate 33, but when turned aside will permit the plate 33, 35 with the attached cone 37, the posts 38, and the heat-radiator 40, all to be lowered to a considerable extent to reduce the height of the hover-space, this change in position being possible by reason of the free play of the 40 smoke-pipe 41 in the opening 43, as already mentioned. As the ends of the slats 44 45 extend over and rest upon the permanent floor 22 of the brooding-chamber they will not be disturbed in this adjustment, but will 45 retain their former position, the posts 38 sliding downward through the holes in the slats, the result being that the plate 39, with the heat-radiator, will be brought nearer to the slats, and thus, in effect, the height of the 50 hover-space will be decreased to any desired extent. In its lowered position the plate 33 rests upon the ledges 46 47, these being so located as to make the height of the hover-space suitable for the very youngest chicks.

55 Within the heat-distributing chamber 37 is an adjustable heat-deflector 48, interposed between the source of heat and the heating-flues in the posts 38 and serving as a means of control over the distribution of the heat passing to these flues. By moving the deflector from side to side on its ball-and-socket joint 50 the heat may be thrown on any desired side of the brooder, the movement of the deflector opening the passage for heat to the flues on one side and obstructing its pas-

sage on the other side, and thus when from any cause, as by a strong wind blowing against one side of the brooder-house, that side is found to be cold more heat may be directed to that part of the house by suitably adjusting the deflector. 70

Having described my invention, what I claim as new, and desire to secure by Letters Patent, is—

1. In a brooder, a floor, a hover-space 75 above the floor, a plurality of heating-flues spaced apart and passing through the floor and traversing and discharging beyond the hover-space, and means for supplying heat to the flues, substantially as described. 80

2. In a brooder, a floor, a hover-space above the floor, a plurality of heating-flues passing through the floor and traversing and discharging beyond the hover-space, a source of heat, and a heat-deflector interposed 85 between the source of heat and the heating-flues, substantially as described.

3. In a brooder, a removable floor composed of slats, a hover-space above the floor, a plurality of heating-flues spaced apart and 90 passing through the floor and through the hover-space, and means for supplying heat to the flues, substantially as described.

4. In a brooder, a floor, a hover-space above the floor, a heat-radiator above the 95 hover-space, a source of heat, and a plurality of heating-flues passing through the floor and traversing and discharging beyond the hover-space and connecting the source of heat and the heat-radiator, substantially as described. 100

5. In a brooder, a floor, a hover-space above the floor, a heat-radiator above the hover-space and vertically adjustable with respect to the floor, whereby the height of the hover-space may be varied, a source of heat, and a plurality of heating-flues passing through the floor and traversing and discharging beyond the hover-space and connecting the source of heat and the heat-radiator, substantially as described. 105 110

6. In a brooder, a floor, a hover-space above the floor, a heat-radiator above the hover-space, a source of heat, and a plurality of heating-flues spaced apart and passing through the floor and through the hover-space and connecting the source of heat and the heat-radiator, substantially as described. 115

7. In a brooder, a floor, a hover-space above the floor, a heat-radiator above the hover-space, a source of heat, a plurality of heating-flues spaced apart and passing through the floor and through the hover-space and connecting the source of heat and the heat-radiator, and an adjustable heat-deflector interposed between the source of heat and the heating-flues, whereby the distribution of heat to the heating-flues may be controlled, substantially as described. 120 125

8. In a brooder, a floor, a hover-space above the floor, a plurality of posts spaced 130

1 apart and interspersed throughout the hover-space, heating-flues within the posts passing through the floor and discharging beyond the hover-space, a smoke-pipe, and 5 means for supplying heat to the flues, substantially as described.

9. In a brooder, a floor, a brooding-chamber above the floor, a heat-radiator within the brooding-chamber, a hover-space between the heat-radiator and the floor, a plurality of heating-flues spaced apart and passing through the floor and traversing and discharging beyond the hover-space, and means for supplying heat to the flues, substantially as described.

10. In a brooder, a floor, a brooding-chamber above the floor, a heat-radiator within the brooding-chamber, a hover-space between the heat-radiator and the floor, a

heat-distributing chamber below the floor, 20 means for supplying heat to the heat-distributing chamber, a plurality of heating-flues spaced apart and passing through the floor and through the hover-space and connecting the heat-distributing chamber and 25 the heat-radiator, and an adjustable heat-deflector within the heat-distributing chamber, whereby the distribution of heat to the heating-flues may be controlled, substantially as described.

30 In testimony whereof I have signed my name to this specification in the presence of two subscribing witnesses.

RALPH M. NORTH.
